CLAIM

The ornamental design for a display screen with animated graphical user interface for vehicle, as shown and described.

DESCRIPTION

The patent or application file contains at least one drawing executed in color. Copies of this patent or patent application publication with color drawing(s) will be provided by the Office upon request and payment of the necessary fee.

1. Display screen with animated graphical user interface for vehicle

1.1 is a perspective image;

1.2 is a front image thereof;

1.3 is a second image thereof;

1.4 is a top image; and

1.5 is a right image thereof.

The appearance of the animated graphical user interface sequentially transitions between the images shown in 1.2 through 1.3. The process or period that one image transitions to another image; forms no part of the claimed design. The solid line perimeter of the display screen and animated graphical user interface are understood to be flush. Rear view is omitted because it does not appear that a part intends for design registration. Bottom view, left side view are omitted because it is each symmetrical to the top view. 1.1 is a perspective image; 1.2 is a front image thereof; 1.3 is a second image thereof; 1.4 is a top image; 1.5 is a right image thereof.

In reproductions 1.1, 1.4 and 1.5, the broken lines are for the purpose of illustrating portions of the display screen that forms no part of the claimed design.
